UNITED STATES PATENT OFFICE

EDWARD J. N. STENT, OF BERGEN POINT, NEW JERSEY, ASSIGNOR TO COOK
& BERNHEIMER, OF NEW YORK, N. Y.

DESIGN FOR A BOTTLE.

SPECIFICATION forming part of Design No. 19,726, dated March 25, 1890.

Application filed February 15, 1890. Serial No. 340,631. Term of patent 14 years.

To all whom it may concern:

Be it known that I, EDWARD J. N. STENT, a citizen of the United States, residing at Bergen Point, New Jersey, have invented and produced a new and original Design for Bottles, of which the following is a specification, reference being had to the accompanying drawings, forming part thereof.

Figure 1 is a sectional view of a bottle, showing my design. Fig. 2 is a top view of the same.

The leading feature of my design is a body portion having substantially the appearance of a cube with plain sides and top, slightly-rounded corners, and a long neck, giving the whole the appearance of a plain low or squatly square body with an abnormally long neck,

the whole being perfectly plane, excepting the enlargement shown on the neck. The sides of the bottle are lettered *a* in the drawings, the top *b*, the bottom *c*, and the neck *d*. The neck is provided with an enlargement *e*. The sides are flat, and all the angles of the body are substantially right angles. The corners are rounded only very slightly, giving the body substantially the appearance of a cube.

What I claim is—

The design for a bottle herein shown and described.

EDW. J. N. STENT.
